Specification for Design.

Patented Dec. 28, 1920.

Application filed June 20, 1918. Serial No. 241,089. Term of patent 14 years.

To all whom it may concern:

Be it known that I, JOHN J. SCULLY, a citizen of the United States of America, and a resident of Bridgeport, Connecticut, whose post-office address is % Columbia Graphophone Manufacturing Company, Bridgeport, Connecticut, have invented a new, original, and ornamental Design for Interchangeable Motor-Boards for Talking-Machines, of which the following is a specification, reference being had to the annexed drawing, forming part thereof.

In said drawing:—

Figure 1 is a plan view; and

Fig. 2 is an edge view of a motor-board embodying my new design.

What is claimed is:—

The ornamental design for an interchangeable motor-board for talking machines, as shown.

In testimony whereof, I have signed this specification.

JOHN J. SCULLY.
